his Attorney,

UNITED STATES PATENT OFFICE.

STEPHEN CHRIST MACK, OF TRENTON, NEW JERSEY.

BENT-WOOD TANK.

No. 915,981.

Specification of Letters Patent. Patented March 23, 1909.

Application filed February 28, 1908. Serial No. 418,380.

To all whom it may concern:

Be it known that I, STEPHEN C. MACK, a citizen of the United States, residing at Trenton, in the county of Mercer and State of New Jersey, have invented certain new and useful Improvements in Bent-Wood Tanks, of which the following is a specification, reference being had therein to the accompanying drawing.

10 This invention relates to an improvement in tanks, and relates particularly to bent-wood tanks.

The object of this invention is the provision of means for forming a portion of the body of the tank, by folding or bending a flexible sheet carrying sections of the tank.

Another object of this invention is the production of a tank which is comparatively simple and inexpensive to construct, and 20 will positively prevent any leakage at the engaging ends of the front and end sections.

With these and other objects in view, the invention consists of certain other novel constructions, combinations, and arrangements of parts, as will be hereinafter fully described and claimed.

In the drawings: Figure 1 is a rear elevation of the tank constructed in accordance with this invention. Fig. 2 is an end elevation of the tank constructed in accordance with the present invention. Fig. 3 is a top view of the front and end sections connected to a sheet or strip of flexible material. Fig. 4 is a top plan view of the body of the tank.

35 Referring to the drawings by numerals, 1 designates the bottom of the tank, upon which is mounted a body portion, secured thereto by any suitable fastening means. The body comprises a back 2 secured to the

40 narrowest ends of sections 3 by any suitable fastening means, as is indicated by dotted lines 4, Fig. 4. Two end sections or portions 3 interlock at their front ends, with the ends of the front section or portion 5. These

45 sections or portions 5 and 3 respectively are secured to a strip of flexible wood, or other material 6, as for instance, veneer, by glue or other adhesive material, constituting fastening means.

50 Any suitable molding 7 may be secured to the sides of the body of the tank, and a top 8 is placed upon the body, and, while it is shown as detachable, it may be fixedly secured to the body by any suitable fastening means.

The outer faces of the front or end sec-

tions or portions are rounded on their outer faces as at 9 and 10, respectively, contiguous to their engaging ends. It is to be noted that, owing to the sections or portions being spaced apart upon the sheet or strip 6, by reason of this curving or rounding of the portions 9 and 10, the same can be folded together, positively causing the fastening means to interlock, as illustrated in Fig. 4. 60 By folding the sections 3 at right-angles to the front section 5, the tongue or projecting portion 11 will be seated in the groove or recess portion 12, allowing the shoulders 13 and 14 and sections 3 and 5 to fit snugly 65 against the flat portions 14 upon opposite sides of the recesses or grooves 12, Fig. 4. The tongues 11 and the recess portions 12 are positioned at an angle to the sides of the front end- portions or sections of the 70 body, so that they will interlock, Fig. 4, when the sheet is folded for placing the end-sections at right-angles to the front section. It is to be noted that the end-sections or portions 3 are notched or cut-out at 15 75 for producing the narrow end- portions of said sections which overlap the ends of the rear portion or section 2. The peculiar construction of the tongue and groove- 80 structure and the beveling or rounding of the contiguous ends of the sections upon their outer faces, providing a very simple 85 interlocking means for fixedly securing the contiguous ends of the front section together, and also forms a tight joint.

90 It will be obvious that I have produced a very simple and efficient tank, as the parts can be quickly folded after assembling upon the flexible sheet or strip of veneer. Furthermore, the top, bottom, back, etc., of the 95 tank can be separated for shipment or transportation, and, owing to the structure, the work of assembling the parts will be greatly facilitated over an ordinary tank.

The inner face of the veneer strip 6 may 100 be steamed between the contiguous ends of the sections to facilitate the bending of the same.

What I claim is:

As an improved article of manufacture, a 105 bentwood tank, comprising a body, said body comprising a back, a single sheet or strip of flexible material provided with front and similarly constructed end sections, said front and end sections being fixedly secured 110 to said sheet, said sheet extending the entire length of the front and end sections, said

end sections each provided, at its outer end, with a shoulder and with an integral extension projecting beyond the shoulder and parallel with the sheet, and each end section is provided upon its inner face, at the inner end, with a curved portion, said inner end being formed at an angle to the inner and outer faces of the section and provided with a tenon having straight parallel sides, said front section provided upon its inner face, near its ends, with curved portions and the ends of said front section being formed at an angle to the front and back faces of said sections, and each end provided with a recess having straight parallel sides adapted to engage the similarly-constructed sides of the contiguous tenon when the sheet is folded

for closing the inner ends of the end section upon the ends of the front section, said shoulders of the end sections fitting against the inner face of the back section and the extensions contiguous to said shoulders covering the entire ends of the back section, and having means extending through the extensions of the end sections and into the ends of the back section and securing the sections together.

In testimony whereof I hereunto affix my signature in presence of two witnesses.

STEPHEN CHRIST MACK.
